UNITED STATES PATENT OFFICE

HENRY ABRAHAMSON, OF CHICAGO, ILLINOIS

SANITARY GARMENT SHIELD

Application filed April 25, 1928. Serial No. 272,733.

My invention relates to appliances worn for hygienic purposes, and more particularly to such appliances as are peculiar to women for purposes of sanitation, and my 5 main object is to provide an appliance which will maintain a sanitary bodily condition.

A further object of the invention is to construct the novel appliance with a method whereby to separate parts which are subject 10 to chafing or inflammation, thus serving to relieve the same.

A still further object of the invention is to design the novel appliance with an absorbent characteristic, to relieve the body of 15 moisture and perspiration.

Another object of the invention is to embody the same in the garment and shape and support it in a manner to hold it in intimate contact with the parts which it is to 20 serve, and in a position independently of that of the garment.

A final, but nevertheless important object of the invention is to construct the appliance on lines of extreme simplicity in order 25 that it may be inexpensively produced and readily handled.

With the above objects in view and any others that may suggest themselves from the specification and claims to follow, a better 30 understanding of the invention may be gained by reference to the accompanying drawing, in which—

Figure 1 is an elevation of an undergarment of the bloomer type, partly broken 35 away to display the novel appliance in section and as worn on the body;

Fig. 2 is a perspective view of the undergarment, partly broken away to show the form of the appliance; and

Fig. 3 is a central vertical section of the garment shown in Figure 1, partly broken away to display a lateral view of one unit of the appliance.

Many efforts have been made in the past 45 to provide comfort and sanitation along such areas of the body as are subject to chafing, burning, inflammation, and lack of sanitation, such efforts being characterized by catamenial appliances, shields, pads and 50 the like. All these expedients were pro-

vided to relieve the conditions mentioned, but in many cases discomfort and heating remained; and in some instances the condition was aggravated. Also, some devices were of such a loose or movable character 55 that they would not remain in place or would not function efficiently for shielding purposes. It has been my intention to devise an appliance which eliminates all the deficiencies of devices of this class in the past and fulfills the above mentioned objects 60 to a satisfactory extent.

Referring specifically to the drawing, 5 denotes the trunk portion and 6 the leg portions of a typical bloomer undergarment. 65 I use such a garment to support and properly position the novel appliance. The latter is constructed of two similar units 7, these being crescent-shaped sections of thin material, such as sheeting, muslin or silk. 70 The units 7 are intended to be positioned along the inside of the leg portions 6 of the garment, having their medial portions in the region of the crotch, and their terminal portions curving in the direction of each leg 75 to a position about half-way across the respective leg portions. Each unit also takes an upward course from the medial area toward the ends.

Each unit 7 is stitched at the bottom of the medial portion to the crotch material of the respective leg portions 6, as indicated at 8. The balance of the units is, however, loose until its extremities are reached, at which point it is again stitched to the front 80 and rear areas of the leg portions 6, as indicated at 9 and 10 respectively. The set of units is thus anchored at the bottom, at the front, and at the rear to the undergarment, thus being definitely located and secured with reference to the latter.

The above location of the appliance renders its medial portions as upward extensions from the crotch of the undergarment. As is well known, undergarments of the 95 bloomer type are worn loose to permit ample freedom of leg movements on the part of the wearer. Thus the crotch of the undergarment is at a distance considerably below that of the body crotch, and it is therefore 100

my purpose to fill the gap between the two crotches by means of my appliance, as is clearly shown in Figure 1.

By locating and fitting the appliance in the manner last-described, I provide a filler which extends fully to the height of the body crotch and therefore separates the limbs at the region of the latter. The crescent design of the respective units follows from the point of separation along each limb so as to augment the separation to areas that are apt to touch or press upon each other when the wearer is seated or bends in one or the other direction. The units thus constitute a complete shield for each limb area.

The material used for the appliance will be chosen to have a highly absorbent quality, so that all perspiration and moisture along the protected areas will be absorbed. The units will be made of 2-ply material, the plies, however, being entirely separated from each other except at the margins where they are connected by stitching or other means. These plies will therefore be capable of shifting with the movements of the wearer, so as to loosen and help dissipate any moisture absorbed by them. Also, the use of two plies for each unit provides a greater capacity for absorbent purposes. Further, the relative shifting of the plies of both units will induce a certain amount of ventilation through the appliance, helping to cool and soothe the affected areas.

While the appliance has been designed and supported to seat closely in the body crotch, yet each of its units will have a certain amount of play and looseness on account of the material being loose from the undergarment along the greater portion of its area. Therefore, ventilation may be assured between the units and the body on one side and between them and the garment on the other side, this action being augmented by the body movements of the wearer. Thus, the appliance is much unlike catamenial and other types of supports or belts, since such supports or belts hug the body closely and are practically immovable; clearly, devices of this kind would seem to promote rather than dissipate heat and friction. On the other hand, the looseness and freedom of my appliance while its position is properly maintained, give it an unmistakable advantage in the respect considered.

It will be seen that I have provided an appliance of this kind which is of the utmost simplicity, since but two patches of the doubled material are used for each garment and could be produced at low expense. The garment need have no special design and suffer no alterations by the connection with my invention. In use, the garment is put on without any special regard or care being given to the improved portion thereof. The garment is simply drawn up on the limbs

in the usual manner, in which event the units of the appliance take their positions without further effort. Also, the appliance has no special fasteners, attachments or loose accessories, so that it is as easy to launder as any other portion of the garment. As garments of this kind are changed every day or every few days, the use of any one appliance will not become so extended as to defeat or impair its purpose.

While I have illustrated and described the invention in the preferred form, it will be evident that the same is capable of many minor changes and refinements and it is my intention to include such changes and refinements as coming within the spirit and scope of the appended claims.

I claim:-

1. A hygienic appliance comprising a bifurcated undergarment, and body shields secured at the crotch portion thereof and extending above said crotch portion so as to occupy the space between said crotch portion and the crotch of the wearer, said shields being erected upon said crotch portion of said garment and positioned to seat upon the contiguous areas of the limbs between the garment crotch and the body crotch.

2. A hygienic appliance comprising a bifurcated undergarment, and body shields carried at the crotch portion thereof and extending above said crotch portion so as to occupy the space between said crotch portion and the crotch of the wearer, said shields being secured inside the garment at the said crotch portion of garment and at the front and rear section of the bifurcated portions of said garment.

3. A hygienic appliance comprising a bifurcated undergarment, and body shields carried at the crotch portion thereof and extending above said crotch portion so as to occupy the space between said crotch portion and the crotch of the wearer, said shields having substantially erect positions and extending from said crotch portion of said garment in outward directions inside the bifurcated portions of the garment, means applied at the bottom of the medial shield portions to secure the same to the crotch portion of the garment, and means applied to the shields in the regions of their extremities to secure the latter to the front and rear sections of the bifurcated portions respectively.

4. A hygienic appliance comprising a bifurcated undergarment, and body shields carried at the crotch portion thereof and extending above said crotch portion so as to occupy the space between said crotch portion and the crotch of the wearer, said shields departing laterally along the inside of the bifurcated portions of the garment, the medial and terminal portions of the shields being secured to the respective bifurcated

portions, and the balance of the shields being free thereof.

5. A hygienic appliance comprising a bifurcated undergarment, and body shields carried at the crotch portion thereof and extending above said crotch portion so as to occupy the space between said crotch portion and the crotch of the wearer, said shields being of two-ply material in which the plies 10 are separated except at the margins of the shields, and means for securing the free ends of said shields to said undergarment.

In testimony whereof I affix my signature.
HENRY ABRAHAMSON.
